UNITED STATES PATENT OFFICE

AUGUSTUS A. BALL, JR., OF LYNN, MASSACHUSETTS, ASSIGNOR, BY MESNE ASSIGNMENT,
TO GENERAL ELECTRIC COMPANY, A CORPORATION OF NEW YORK.

HYDROCARBON-BURNER.

No. 901,415.

Specification of Letters Patent.

Patented Oct. 20, 1908.

Application filed January 24, 1902. Serial No. 91,014.

To all whom it may concern:

Be it known that I, AUGUSTUS A. BALL, Jr., a citizen of the United States, residing at Lynn, in the county of Essex, State of Massachusetts, have invented certain new and useful Improvements in Hydrocarbon-Burners, of which the following is a specification.

The present invention relates to burners 10 utilizing hydro-carbon vapor for fuel, and more especially for those in use on self-propelled vehicles.

The object of the invention is to improve the construction of hydro-carbon burners, 15 whereby their action may be rendered more certain and satisfactory.

The scope of the invention will be more fully set forth in the description and in the claims appended thereto.

In the accompanying drawings which illustrate an embodiment of my invention, Figure 1 is a side elevation of a vehicle with a portion of the side broken away to show the boiler and burner; Fig. 2 is a partial vertical section of the burner; Fig. 3 is a plan view of the burner with certain of the parts broken away; Fig. 4 is a detail sectional view illustrating one of the air carrying passages and fuel openings; Fig. 5 is an enlarged detail view showing the injection tubes for the burner; Fig. 6 is a plan view of the vaporizer showing its relation with respect to the burner; Fig. 7 is a vertical section of the valve for controlling the admission of fuel to the injection tubes; Fig. 8 is a horizontal section taken on line 8—8 of Fig. 7, and looking in the direction of the arrow; Fig. 9 is a detail vertical section taken on line 9—9 of Fig. 7, looking in the direction of the arrow; Fig. 10 is a perspective view of a holder for an injection tube; and Fig. 11 is a diagrammatic view of the thermostat employed to actuate the fuel valve.

Referring to Fig. 1, 1 represents a vehicle body of any suitable construction, having driving wheels 2, and steering wheels 3, the latter being moved by the lever 4. Motion is imparted to the driving wheels by the engine 5, through differential gearing, in any suitable manner. The boiler 6 is enclosed by the sides of the vehicle body, and situated below the boiler and preferably concentric therewith, is one of my improved burners.

In describing my invention particular reference will be made to its adaptability for vehicle work, but it is to be understood that the burner may be utilized for other classes of work without departing from the spirit 60 of my invention.

Referring more particularly to Figs. 2 to 4, the construction of the burner will be described. The burner comprises top and bottom circular plates, 7 and 8, which plates are 65 provided at the periphery with flanges 9 that extend in opposite directions, and engaging therewith is a vertically extending strip of metal 10, which is secured in place by turning or bending its edges over the flanges or 70 in any suitable manner. The plates 7 and 8, together with the vertically extending piece or side wall 10, form a chamber for receiving hydrocarbon vapor from the injector tubes. Extending vertically through the top 75 and bottom plates, is a plurality of air-carrying tubes. These tubes are riveted over at the ends, as is clearly illustrated in Fig. 4, and thus serve to hold the plates in fixed relation, besides furnishing the necessary 80 amount of air to cause proper combustion. Surrounding each of the air carrying tubes is a plurality of fuel openings 12, formed in the top plate 7, and it is through these holes that the fuel from the chamber 13 passes. 85

The burner is divided into sections, the inner or central section being in operation at all times when the system is in operation, and is so designed that it will furnish sufficient heat to keep up the necessary steam 90 pressure when the vehicle is standing idle. It is preferably located directly under the center of the boiler, and since it is kept in continuous operation, it in effect constitutes a pilot burner. By arranging the section 95 as shown, all danger from extinguishment, due to gusts of wind, is prevented, and losses due to radiation are decreased to a minimum. Surrounding the center of the burner, and preferably concentric therewith, is a second or intermediate section 14; this section is intended to be in operation when the demand for steam increases. Surrounding the intermediate section 14, and concentric therewith, is an outer section 15, which comes into service only when the demand on the boiler for steam reaches its maximum. In other words, the burner is provided a burner which is divided into three sections, the innermost section being in operation at all times, the intermediate section being in operation when the demand for steam increases, and the outermost section being in operation when the demand reaches its maximum.

burnished thereby is progressively increased in a step-by-step manner when the demand on the boiler for steam is increased, and vice versa. The central section is separated from the intermediate section by a partition 16, which is substantially hexagonal in shape, the two walls extending parallel with the central injection tubes, being, however, somewhat longer than the other sides. The pieces forming the partition 16 may be secured in place in any desired manner; in the present instance they are held in place by rivets 17, which pass down through the top and bottom plates 7 and 8, and which are staggered so as to support the partition on each side. The intermediate section is separated from the outer section by a partition 18, which is also hexagonal in shape, the side walls of which are parallel with those on the inner section. The sections of the wall are retained in place by the rivets 19, which pass through the top and bottom plates, and which are staggered so as to support the wall from both sides. I have found the distribution of the air-carrying tubes 11, shown in Fig. 3, to be very satisfactory, in that it permits of even, or substantially even, spacing, more so than when the partitions are cylindrical. I have stated that the sections of the burner were concentrically arranged; I do not mean by this that they are, or need to be, mathematically concentric, but in so far as it is possible one section should be arranged to surround the other, and the second section should be of considerable greater capacity than the inner section. In the present instance, the central section is provided with twenty-eight air-carrying tubes with the surrounding burner openings 12. The intermediate section is provided with seventy air-carrying tubes and the surrounding fuel openings, and the outer section is provided with sixty-seven air-carrying tubes having surrounding fuel openings. These sections are entirely separated from each other, and the gases do not mingle until after they have passed through the fuel openings 12, into the fire chamber adjacent to the boiler tubes.

Fuel is admitted to the central section by a removable injection tube 20, Fig. 4, having tightly tapered sides and a conical end. The object in making this, as in the other injection tubes, removable is for the purpose of inspection and cleaning. The tube 20, being the injection tube 20, and fitted into the partitions or walls 16 and 18, is a tubular projection 22, on the outer end of which is a tubular projection 23. The outer ends of this tube 20 are provided with holders 24, designed to receive the injection

holders will be described. The end of the holder, which projects into the burner, is cylindrical, while the outer end is provided with two parallel sides 27, which are united by a curved portion of the tube. The parallel side portions 27 are adapted to be riveted to the partition 23 and thus assist in forming one of the sections of the burner. The periphery of each injection tube is slightly tapered, so as to make a good working fit with the interior of the holder, the friction between the parts being sufficient to retain the tubes in place. The holders are preferably made of tubing and are formed by suitable dies.

The left hand ends of the partitions 18 and 23, Fig. 5, are united by the Z shaped piece 28, which serves to prevent the vapor admitted to the outer section or chamber 15 from mingling with the vapor in the intermediate section or chamber 14. The partition 18, which separates the intermediate from the outer section, terminates in a short section 29 which extends to the circular surrounding wall 10. In mounting these partitions in place it is unnecessary to make especially fine joints between the parts, since the escape of a slight amount of vapor from one section to the other does no harm; it will merely pass through the fuel openings 12 of an adjacent section and thence to the combustion chamber, where it will be consumed.

The burner as a whole is inclosed within the extension of the boiler casing 30, and is sustained in place by the brackets 35. Surrounding the burner, but separated therefrom by a space, is a casing or shield 36, having a closed base and a side wall, which casing is secured to the boiler or other support by clips 37. By this arrangement a space is left between the side wall and the boiler casing, so that the air entering the burner will be more or less warmed, and the liability of the flame being blown out by gusts of wind is reduced to a minimum.

In order to feed fuel to the sections of the burner in proper amounts and at proper times an automatic regulator is provided, which may be operated in any suitable manner; I have found that satisfactory results may be obtained with a thermostat. The regulator shown includes one nozzle for feeding fuel to the central injection tube 20, or one leading to the central section of the burner, at all times when the system is in operation. A second nozzle feeds fuel to the intermediate section and is in operation when the demand for steam is normal or thereabouts. A third nozzle feeds fuel to the outer section of the burner and is in operation only when the demand for heat is greater than that supplied by the central and intermediate sections.

Referring to Figs. 7 to 9 inclusive, 38

represents the main body of the regulator and is provided with a vapor admitting opening 39, the latter being in communication with the vaporizer and fuel tank. The opening 39 communicates with an L-shaped conduit 40, and from this conduit are three openings 41, 42 and 43. The opening 41 is in communication at all times with the conduit 40, and the amount of vapor which can pass therefrom into the central nozzle 44 is governed by the manually-adjusted valve 45. When the system is in proper adjustment sufficient fuel should flow from the tank and vaporizer, through this nozzle into the central section of the burner, to furnish a blue, steady flame of sufficient intensity to maintain the steam pressure on the boiler, and also to resist any tendency of the wind to blow out the flame. Being so well protected there is, of course, little or no opportunity for the wind to act directly on the flame. The supply of fuel to the other nozzles 46 and 47 is under the control of an automatically-actuated valve. This valve is provided with an elongated stem 48, which is provided with a conical shoulder on the lower end, and a reduced portion 49, that acts as a piston valve. The conical shoulder is seated in a corresponding depression or opening in the body of the regulator. The opening directly below the conical seat is somewhat larger than the reduced portion 49 of the valve stem. This is arranged so that when the valve stem is slightly raised, vapor will pass from the conduit 40 through the opening into the passage 42 leading to the nozzle 46, the latter supplying fuel to the intermediate burner section. When the end 49 of the valve stem is raised still higher so that it enters the enlarged opening, free communication is afforded between the conduit 40 and the nozzle 47, the latter supplying fuel to the outer burner section. With the valve stem in the raised position just described, the burner will be supplying its maximum amount of heat for a given pressure on the fuel system. To put the matter in a different way, the regulating valve is provided with as many seats as there are outer burner sections, and the movement of the valve successively cuts sections of the burner into and out of operation. The valve stem is suitably guided at the bottom, and is provided with a stuffing box 50 to prevent the escape of vapor at this point. The upper end of the stem is provided with an enlarged head 51, which, when the pressure on the diaphragm 52 exceeds a certain amount, will be forced downward until the valve seats itself on the body portion of the regulator, as is shown in Fig. 7. Surrounding the valve stem is a screw threaded plug 53, which serves as a guide for the stem, and also as an adjustable abutment for the coiled

compression spring 54, located between it and the enlarged head. The spring tends at all times to lift the valve stem and admit more fuel to the burner, while the thermostat is arranged to oppose this action and close the fuel openings. 70

In order to regulate the discharge of fuel from the nozzles 46 and 47 manually-actuated valves 55 and 56 are provided, as is shown in Fig. 9. It is intended that these 75 valves shall be adjusted once for all, after which further consideration is unnecessary.

The particular burner disclosed in the drawings is intended for use in connection with kerosene, but any other suitable fuel 80 may be employed. In order that the liquid fuel received from the tank 57, Fig. 1, shall enter the burner in the form of vapor a suitable vaporizer is used which vaporizer is preferably of the character shown in Fig. 6. 85 It will be seen that the configuration of the pipe conforms closely to the arrangement of the burner sections, extending centrally and lengthwise over them, that is to say, the pipe or tube from the point 58 to point 59 is affected by the heat from the flames due to the burner openings in the outer section. At 59 the tube turns back and from this point to point 60 the tube is affected by the heat due to the flames of the intermediate burner section, while the section of the tube from 60 to 61 is affected by the heat of the flames from the inner burner section. Each portion of the vaporizer passes through the zone of maximum intensity of heat due to the 100 burner section immediately adjacent thereto, and is heated directly by its flame. By this arrangement the capacity of the vaporizer to furnish vapor to the burner sections is progressively increased in a step-by-step 105 manner as the activity of the burner is also increased in a step-by-step manner, and by a corresponding amount. In other words, when one section only of the burner is in operation that portion of the tube between 110 60 and 61 is sufficient to furnish the necessary amount of vapor. When two sections of the burner, the center and intermediate, are in operation, the vaporizing tube between points 61 and 59 is sufficient to produce the necessary vapor for maintaining them in operation, and when the total burner is in operation the vaporizing tube between 61 and 58 will furnish the necessary amount 115 of vapor. The vaporizing tube is so designed that its heating effect will produce the necessary vapor without causing the fuel therein to carbonize, or the temperature of the oil to be reduced below a certain point as it passes through it. The outer end of the 120 vaporizing tube is connected by the pipe 62 with the fuel tank 57, a suitable valve being provided in this pipe whereby the supply of fuel may be cut off. The opposite end 63 of the vaporizer tube is connected by a suitable 125 130

coupling with the passage 39 of the regulator.

In Fig. 11 the burner is shown in position below the boiler with the regulator 38 connected to the thermostat 64. The thermostat comprises a coil of pipe filled with some such material as kerosene and is located at the upper end of the boiler. As the temperature of the fire gases within the boiler changes, the pressure within the thermostat varies accordingly. The thermostat is not claimed herein but forms the subject matter of a separate application filed by me June 2, 1902, and bearing Serial Number 109,872.

15 A burner constructed in accordance with my invention is quick to start, is substantially smokeless and odorless in operation, and is noiseless and reliable under all conditions of running, whether the flame be limited to one, two, or three sections of the burner. When the output required from the burner is small, the automatic regulator cuts out the outer and intermediate sections of the burner, and this without decreasing the 25 gas pressure within the burner body. This is an important consideration, for in those cases where the gas pressure in the burner is decreased the flame becomes unstable and is liable to be extinguished by gusts of wind 30 or pulsating action of the vaporizer; it also causes objectionable odors. The present method of control also has the advantage of permitting a constant air pressure to be maintained on the oil tank as distinguished 35 from those systems wherein the pressure has to be reduced when the burner is to be operated near its minimum range of capacity. Since radiation and losses from those parts 40 of the boiler near the center are largely absorbed by the outer portions, it is desirable, with the idea of obtaining high economy, to apply heat as nearly as possible to the center of the boiler, and with the burner above described it will be seen that this advantage is 45 obtained. The burner possesses the further advantage that on very light loads, or when the vehicle is standing, the central portion only is heated, thus giving a most economical condition of operation.

50 In accordance with the provisions of the patent statutes, I have described the principle of operation of my invention, together with the apparatus which I now consider to represent the best embodiment thereof; but 55 I desire to have it understood that the apparatus shown is only illustrative and that the invention can be carried out in other ways.

What I claim as new and desire to secure 60 by Letters Patent of the United States, is.—

1. In combination, a burner having a chamber divided into independent concentric sections, a vaporizing conduit which extends over a plurality of the sections and 65 substantially along the median lines thereof

to convey fuel through the zone of maximum flame of one section after another to vaporize it, and means receiving vapor from said conduit and supplying it to the burner sections.

2. In combination, a burner having a chamber which is divided into a plurality of sections, a continuous vaporizing tube extending over each of the sections and substantially along the median lines thereof, 70 means at the discharge end of the vaporizing tube which supplies fuel to one section, and means receiving fuel from said tube and supplying it to the other sections in successive order.

3. In combination, a burner having a chamber divided into concentric sections, a vaporizing conduit comprising as many portions as there are sections which are connected end to end and are arranged one over 80 each section, the inlet-end of the conduit being so located that fuel is conveyed over one section after another beginning with the outer section, and means for successively cutting the chamber sections into service 85 in an order beginning with the inner section and ending with the outer.

4. In combination, a burner of the chamber type, partitions within the chamber which separate the same into independent 95 sections of which one is adapted to be in continuous operation and the others to be successively cut into service, air carrying tubes in each section, a vaporizer so arranged 100 relatively to the sections that fuel flows successively over the sections beginning at the section adapted to be last cut into service and ending at the section in continuous service, nozzles for discharging vapor from the vaporizer to the sections, and means controlling the sections other than the one in continuous service.

5. The combination of a burner which is provided with a chamber divided into sections and with fuel openings for each of the 110 sections, a vaporizing tube having its whole length coiled substantially along the median lines of all the sections in successive order, a device which controls the number of sections used during varying conditions of operation and thus correspondingly varies the capacity of the vaporizing tube, and means independent of said device for supplying fuel to one section continuously during operation of the burner.

6. In combination, a burner of the chamber type divided into several sections which are provided with unequal numbers of vapor-discharging openings, a vaporizing conduit formed of several portions of different lengths and arranged with the longest portion over the burner section having the greatest number of openings and the shortest portion over the section having the smallest number of openings and the intermediate 125 130

portion or portions over the section or sections having an intermediate number or numbers of openings, the fuel entering the longest portion and flowing thence through 5 the intermediate portions to the shortest portion, and means for successively supplying vapor from the shortest portion to the sections beginning with the section having the smallest number of openings and ending 10 with the section having the greatest number of openings.

7. In combination, a burner having a chamber divided into concentric sections which vary one from another as to capacity, 15 vaporizing conduits which also vary in capacity one from another and are connected to form a single vaporizer extending successively over the sections and substantially along the median lines thereof, and means 20 for supplying vapor from the vaporizer to the chamber sections successively.

8. In a burner, the combination of a top-plate containing fuel openings arranged in polygonal rows, a bottom-plate, air-carrying tubes arranged in rows corresponding to the openings and secured to both plates, an inclosing outer wall secured to the plates, polygonal partitions arranged to divide the space between the plates into separate compartments and extending parallel to and between the rows of openings and tubes, and means for securing the partitions in place.

9. In a burner, the combination of top and bottom-plates flanged at their peripheries, a 35 metal strip coöperating with the plates to form a chamber and having its edges turned over the flanged portions of the top and bottom-plates, air-carrying tubes having their ends extending through the plates and expanded, partitions dividing the said chamber into substantially concentric sections, and rivets arranged alternately on opposite sides of the partitions in staggered relation and having their ends riveted in the top and 45 bottom-plates.

10. In a burner, the combination of top and bottom plates, a wall for inclosing the plates at the ends, partitions for dividing the space between the plates into center, outer 50 and intermediate compartments, an injection tube which delivers vapor to the center section or compartment, a holder for the tube which extends through the outer and intermediate compartments, a second injection tube which opens into the intermediate compartment, and a third injection tube which 55 opens into the outer compartment.

11. In a burner which is arranged in concentric sections, the combination of a tube 60 for conveying fuel to a central section, tubes for conveying fuel to the other sections, a vertically extending wall or partition, and holders for the last mentioned tubes which are secured to the partition.

65 12. In a burner, the combination of top

and bottom plates that form a gas chamber, an injection tube, and a sheet-metal holder for said tube comprising a tube having a cylindrical portion which makes a working fit with the injection tube, and a second portion which is provided with a flat wall by means of which the holder is secured to the burner casing, the flattened portion of the tube being arranged to engage with the plates and assist in forming the gas chamber. 70

13. In combination, a burner composed of a central section and two surrounding sections which have open adjacent ends, a nozzle tube extending through the surrounding sections into the central section, a nozzle tube 80 extending into the open end of each of the surrounding sections, a nozzle for each tube, a common source of fuel supply connected with the nozzles, and a single means for opening and closing only the nozzles which 85 discharge into the surrounding sections.

14. In combination, a burner which is divided into a plurality of sections located one within the other, a single nozzle for each section, an automatic regulator controlling the 90 nozzles for successively cutting the sections into and out of service, and a vaporizer which is so located with respect to the sections that as they are successively and automatically cut into and out of action the 95 effect of the vaporizer is correspondingly varied.

15. In combination, a burner of the chamber type comprising a central section and a plurality of surrounding sections which have 100 juxtaposed open ends, nozzle tubes for the sections which are radially disposed about a point central to the open ends of the surrounding sections, nozzles extending into the tubes one of which is permanently open to 105 a source of fuel supply, and a single means for opening and closing the other nozzles successively.

16. In combination, a burner which is divided into a plurality of concentric sections, 110 a vaporizer tube which follows the contour of the outer section, then turns in the opposite direction and follows the contour of the inner sections, and a nozzle for feeding fuel to a burner section which nozzle is connected to that end of the vaporizer tube located in proximity to the inner burner section. 115

17. In combination, a sectional burner with a vaporizer tube located above the burner 120 which follows the general shape of an outer section, then turns back and follows the general shape of an intermediate section, after which it turns and crosses an inner section whereby the total effect of the vaporizer is 125 modified in accordance with the number of active burner sections.

18. In a burner, the combination of means for dividing it into a plurality of sections, each section having a plurality of fuel open- 130

ings, a single nozzle for each section, a regulator that acts to successively cut the nozzles into and out of service, and a vaporizer comprising a single flat coil which occupies a 5 horizontal plane above the fuel openings in all of the sections and closely conforms to the outline of said sections, so that when one or more sections are cut into or out of service, the effect of the vaporizer is correspondingly varied and substantially in accordance 10 with the demand for vapor.

19. In a burner, the combination of a pair of plates which are separated to form a gas chamber, air-carrying tubes which pass 15 through the plates, means for dividing the chamber into sections, means for successively admitting fuel to or cutting it off from the sections, a casing into which the chamber closely fits, and a shield for preventing the 20 air from directly passing to the tubes, comprising a portion which extends across the

burner and side portions which extend at an angle thereto around the lower end of the casing and which are separated from the casing by an air space.

25

20. In combination, a burner comprising a chamber having a number of independent concentric sections, means for controlling the supply of vapor to the burner sections, and a vaporizing conduit for supplying 30 vapor to all of the burner sections which extend over a plurality of the sections in series so that as they are brought into and out of action by the controlling means, the action of the vaporizer is correspondingly varied.

35

In witness whereof I have hereunto set my hand this twentieth day of January, 1902.

AUGUSTUS A. BALL, JR.
